(57) **CLAIM**

The ornamental design for a pen case, as shown and described.

DESCRIPTION

1. Pen case

1.1 : Front

1.2 : Right

1.3 : Back

1.4 : Top

1.5 : Bottom

1.6 : Enlarged end view

1.7 : Perspective view during opening state

1.8 : Right side view of the open state

1.9 : Top view of the open state

This product is a pen case that can be closed by four rectangular magnets embedded in four sides; and as shown in a perspective view during opening state and a right side view of the open state, it can be opened into a box shape and used; fig. 1.1 is a front view of a pen case showing the new design; fig. 1.2 is a right view thereof, a left view thereof being a mirror image of the right view; fig. 1.3 is a back view thereof; fig. 1.4 is a top view thereof; fig. 1.5 is a bottom view thereof; fig. 1.6 is an enlarged end view thereof taken along the line 1.6-1.6 in fig. 1.1; fig. 1.7 is a perspective view during opening state thereof; fig. 1.8 is a right side view of the open state thereof; fig. 1.9 is a top view of the open state thereof. The oblique shade lines represent a transparent or

(Continued)

semi-transparent surface, and the claimed design is not limited to any specific color or material.
